UNITED STATES PATENT OFFICE.

OLIVER ELLSWORTH BUCKLEY, OF EAST ORANGE, NEW JERSEY, ASSIGNOR TO WESTERN ELECTRIC COMPANY, INCORPORATED, OF NEW YORK, N. Y., A CORPORATION OF NEW YORK.

METHOD OF PREPARING VACUUM-TUBES.

1,272,374.

Specification of Letters Patent. Patented July 16, 1918.

Application filed December 30, 1915. Serial No. 69,418.

To all whom it may concern:

Be it known that I, OLIVER ELLSWORTH BUCKLEY, a citizen of the United States, residing at East Orange, in the county of Essex and State of New Jersey, have invented certain new and useful Improvements in the Methods of Preparing Vacuum-Tubes, of which the following is a full, clear, concise, and exact description.

10 This invention relates to the preparation of vacuum tubes, in particular to thermionic devices having a heated cathode, an anode and an auxiliary electrode.

Its object is to provide for heating the anode by vigorous bombardment of electrons without endangering the cathode, such bombardment being desirable in order to drive out gases occluded in the anode.

This object is accomplished by limiting 20 the current in the tube by applying a negative charge to the auxiliary electrode, and by then applying a large voltage between anode and cathode by which the energy of the striking electrons is increased to a value 25 larger than normal.

In the construction of vacuum tubes in which it is desired to maintain a high vacuum, it has been found that unless the electrodes and walls of the vessel have been 30 subjected to a vigorous preliminary treatment, the gases occluded by them will slowly leak out with the result that the vacuum is soon decreased and ionization by collision can then take place. This preliminary treatment is usually carried out by heating the 35 walls of the vessel externally and by directing a stream of electrons toward the anode. The effect of these electrons, on striking the anode, is to liberate all ionizable matter 40 which may be removed. In this process it is essential that the energy of the striking electrons shall be considerably greater than that during normal operation.

Now it has been found that in preparing 45 vacuum tubes it is not allowable to draw from the cathode a much larger current than is used in normal operation, for the effect of that treatment is to disintegrate the cathode. The present invention insures that the electrons striking the anode shall do so under 50 the influence of a large voltage and consequently with large kinetic energy, while at

the same time this large voltage is not able to draw more than normal current from the cathode.

In a thermionic device of the type described, if the potential of the auxiliary electrode is made negative with respect to the cathode, a larger voltage between anode and cathode is necessary to produce the same 60 current from the cathode as would appear in the absence of such a voltage applied to the auxiliary electrode. But the kinetic energy of the electrons striking the anode increases with the increased voltage, and 65 it is therefore possible, by applying a negative potential to the auxiliary electrode, to increase the voltage effective in driving electrons to the anode very much above the normal value, while maintaining the current at its normal value. By this process 70 the vigorous bombardment of the anode is possible without drawing more than normal current from the cathode.

This invention will be more completely 75 described in connection with the drawing, in which the single figure shows apparatus which may be used for carrying out the invention and in which 1 represents a vacuum tube of the type considered, consisting of an evacuated vessel containing cathode 5, anode 6 and auxiliary electrode 7. This vessel is inclosed in an oven 2 which may be heated externally. The glass tubing 3 serves to connect the tube with a molecular pump 4 or other suitable means for exhausting it. The liquid air-trap 10 is included in this line of tubing for the usual purpose. The filament 5 is heated by means of alternating current furnished to it 80 through the medium of the transformer 8, whose primary winding is energized by means of the source of alternating current, not shown in the drawing. The voltage between anode and cathode is supplied by 85 means of the direct current generator 9, while the electromotive force required to maintain the auxiliary electrode negative with respect to the cathode is obtained from the battery 11, whose negative pole is connected to the auxiliary electrode.

During the process of evacuation the pump is operated, the filament heated and a discharge started between anode and

cathode. The battery 11 is then applied and the voltage of the generator 9 increased. The current through the tube is adjusted to approximately normal value and the bombardment of the anode at the increased voltage is continued until no evidence of gaseous ionization in the tube can be detected.

As an example of the voltages employed in one type of tube, it has been found that 10 in the early part of the process a maximum of about 200 volts can be maintained between the cathode and the anode. By applying 110 volts between the cathode and the auxiliary electrode, making the latter negative, a maximum of 500 volts or more may 15 be obtained with consequent more rapid release of gas from the anode. In the later stages of exhaust a potential difference of 750 volts or more may be maintained by the 20 use of the negative auxiliary electrode, while if that electrode were disconnected it would not be more than 550 volts. A further advantage of this method is that during the process of bombardment the negative auxiliary electrode attracts to itself the greater 25 part of the positive ions released by the electron discharge, and thereby prevents the bombardment of the cathode by these ions, which bombardment, as is well known, tends 30 to disintegrate the cathode.

What is claimed is:

1. The method of preliminary treatment of a vacuum tube containing a heated cathode, an anode and an auxiliary electrode, which method consists in evacuating said tube and before said evacuation is completed in performing the following steps, *i. e.* in maintaining an electron discharge between said cathode and anode and in applying between said auxiliary electrode and said cathode a voltage which shall limit the current to a given value while permitting a large voltage between anode and cathode whereby the energy of the electrons striking the anode shall be large. 40

2. The method of preliminary treatment of a vacuum tube containing a heated cathode, an anode and an auxiliary electrode, which method consists in evacuating said tube and before said evacuation is completed in performing the following steps, *i. e.* in maintaining the auxiliary electrode at a negative potential with respect to the cathode and in applying between anode and cathode a voltage sufficient to maintain a 50 desired current in the tube. 55

In witness whereof, I hereunto subscribe my name this 28th day of December, A. D., 1915.

OLIVER ELLSWORTH BUCKLEY.
